UNITED STATES PATENT OFFICE.

WILLIAM G. DUNHAM, OF CHICAGO, ILLINOIS.

CAR-AXLE-BOX LID.

No. 851,077.

Specification of Letters Patent.

Patented April 23, 1907.

Application filed November 1, 1905. Serial No. 285,425.

To all whom it may concern:

Be it known that I, WILLIAM G. DUNHAM, a citizen of the United States, residing at Chicago, in the county of Cook and State of Illinois, have invented certain new and useful Improvements in Car-Axle-Box Lids; and I do hereby declare the following to be a full, clear, and exact description of the invention, such as will enable others skilled in the art 10 to which it appertains to make and use the same.

My present invention relates to car axle box lids of the general character set forth and broadly claimed in my Patent 803,155 of date 15 October 31st, 1905, entitled "Car axle box lid" and is particularly designed as a modification of the device disclosed and claimed in my pending application Serial No. 285,016, filed of date October 30th, 1905 entitled 20 "Car axle box lid."

The present invention consists of the novel devices and combinations of devices herein-after described and defined in the claims.

In the accompanying drawings which illustrate my invention, like characters indicate like parts throughout the several views.

Figure 1 is a view principally in side elevation, but with some parts broken away and with some parts sectioned, illustrating the invention applied to a car axle box. Fig. 2 is a vertical section taken approximately on the line x^2x^2 of Fig. 1, some parts being left in full, and Fig. 3 is a view on the same line as Fig. 2, but showing the lid in an open position, some parts being broken away.

The numeral 1 indicates the axle-box and the numeral 2 a portion of the axle. The box in line with its mouth opening is formed with a transversely extended upwardly projecting fulcrum rib 3 and with laterally spaced bearing lugs 4. The lid 5, which is preferably constructed of malleable iron, is bulged inward at 6 and is formed at its extreme upper edge with a semi-cylindrical fulcrum seat 7 that engages and rotates upon the rounded upper edge of the fulcrum rib 3. Said lid is also formed with a perforated lug 8 that projects inward from its bulge 6. Webs on the sides of the lid at the ends of the fulcrum seat 7 engage the ends of the fulcrum rib 3 to hold the lid in working position against transverse movements.

The numeral 11 indicates a bolt which is provided with a transversely extended shaft 55 or head portion that is journaled in the perforations of the two bearing lugs 4. The bolt

11 and its head 12 constitute what may be termed the "T-bolt". The bolt 11 is provided with a projecting collar or flange 14 and its free end works through the perforation of the lid lug 8 and is provided below the said lug with a stop pin 15. A coiled spring 16 is placed on the bolt 11 and is compressed between the collar 14 thereof, and the lug 8 of the lid. In this construction, it will be noted that the axis of the shaft-like head 12 of the T-bolt is located inward of the plane of the mouth opening of the box and inward of the axis of the rounded upper edge of the fulcrum rib 3. In the closed position of the lid, 60 the spring 16 of the spring thrust device exerts a force on a line that obliquely intersects the plane of the mouth opening of the box and extends below the fulcrum rib 3, so that at such time it tends to hold the lid closed 65 and tends to hold the lid seated at the bottom, top and both sides of the face of the mouth opening of the box.

When the lid is moved from its closed position shown in Fig. 2 into its open position 80 shown in Fig. 3, the line of strain of the spring 16 is carried to and then past a dead center with respect to the axis of the head 12 and the axis of the rounded portion of the rib 3, so that in the open position of the lid, 85 the spring exerts a force tending to hold said lid open. The spring thrust device made up of the bolt 11 and the spring 16 therefore has an angular movement both in respect to the box and to the lid, when the lid is moved 90 from a closed to an open position, or vice versa. In all positions of the lid, the said spring exerts a force which tends to maintain engagement between the seat 7 of the lid 5 and the fulcrum rib 3 of the box. The fulcrum rib 3 and the seat 7, of course, constitute the lid hinge, the axis of which is the axis of rotation of the said seat upon the said rib. The stop pin 15 in the free end of the bolt 11 engages the lug 8 of the lid to limit 95 the extreme opening movement of said lid, as shown in Fig. 3.

What I claim and desire to secure by Letters Patent of the United States is as follows:

1. The combination with an axle box and a lid hinged thereto, of a spring thrust device reacting directly against a part rigid with the lid and against a seat in a fixed base of resistance inward of the axis of the lid hinge; said spring thrust device having an angular oscillatory movement both in respect to the lid and the box, and disposed that its line

of force intersects the mouth of the box when the lid is closed, and the spring of which thrusts outward on the lid to open the same, substantially as described.

5 2. The combination with an axle box and a lid hinged thereto, of a spring thrust device reacting directly against a part rigid with the lid and against a seat in a fixed base of resistance inward of the mouth opening of the lid, said spring thrust device having an angular oscillatory movement both in respect to the lid and the box, and so disposed that its line of force obliquely intersects the mouth of the

box when the lid is closed, the spring of which thrusts outward on the lid to open the same, and said lid and its support being provided with means whereby movement of the lid carries said thrust device from one side to the other of a dead center, substantially as described.

20 In testimony whereof I affix my signature in presence of two witnesses:

WILLIAM G. DUNHAM.

Witnesses:

EDWARD DENEGRE,
H. EDWARD.
